CLAIM

The ornamental design for a hose reel, as shown and described.

DESCRIPTION

FIG. 1 is a perspective view of a hose reel according to our new design;

FIG. 2 is a rear view thereof;

FIG. 3 is a front view thereof;

FIG. 4 is a right-side view thereof;

FIG. 5 is a left-side view thereof;

FIG. 6 is a top plan view thereof; and,

FIG. 7 is a bottom plan view thereof.

Conventional shading is illustrated for purposes of highlighting the line drawings, but forms no part of the claimed design.

The broken lines in the drawings depict portions of the hose reel that form no part of the claimed design.

Any unshaded surfaces shown in broken or between solid and broken lines form no part of the claimed design.
